UNITED STATES PATENT OFFICE.

DANIEL C. CAHALANE, OF HILLSDALE, NEW JERSEY.

DESIGN FOR AN INKSTAND.

Application filed July 21, 1923. Serial No. 6,816. Term of patent 14 years.

To all whom it may concern:

Be it known that I, DANIEL C. CAHALANE, a citizen of the United States, residing at the town of Hillsdale, in the county of Bergen and State of New Jersey, have invented a new, original, and ornamental Design for Inkstands, of which the following is a specification, reference being had to the accompanying drawing, forming part thereof.

The figures show a plan view and a vertical elevational view of an ink stand, showing my new design.

My design consists of a circular base with a dome mounted thereon which is surmounted by a neck having a mouth opening to receive a cork.

I claim:

The ornamental design for an inkstand, as shown and described.

DANIEL C. CAHALANE.
